United States Patent Office

Des. 214,383
Patented June 10, 1969

214,383

FIREPLACE TOOL HANGER

William F. Johnson, 9 Roundabout Road,
Smithtown, N.Y. 11787

Filed June 14, 1967, Ser. No. 7,475

Term of patent 14 years

Int. Cl. D8—03

U.S. Cl. D33—17

The figure is a perspective view of a fireplace tool hanger showing my new design.

I claim:

The ornamental design for a fireplace tool hanger, substantially as shown.
